UNITED STATES PATENT OFFICE.

HERMAN KERNGOOD, OF BALTIMORE, MARYLAND.

DESIGN FOR A HOOK FOR GARMENT-FASTENERS.

SPECIFICATION forming part of **Design No. 25,912**, dated **August 11, 1896**.

Application filed June 24, 1896. Serial No. 596,807. Term of patent 7 years.

To all whom it may concern:

Be it known that I, HERMAN KERNGOOD, a citizen of the United States, residing at the city of Baltimore and State of Maryland, have 5 invented and produced a new and original Design for Hooks for Garment-Fasteners, of which the following is a specification.

In the accompanying drawings, which form part of this specification, Figure 1 represents 10 a perspective of the hook, and Fig. 2 a like view of the hook inverted.

The following are the leading features of the design.

The hook A comprises a plate or body *a*, 15 provided with curved or concave sides, lateral extensions *b*, and a rearward extension

c, an opening *d* in the bent portion of the hook, which is curved backward from the front end of the plate, and the opening *d* extends back into the plate. In the inner end 20 of said opening is a V-shaped projection *f*, which extends forward under the bill *e* of the hook.

What I claim is—

The design for a hook for a garment-fas- 25 tener, substantially as shown.

In testimony whereof I affix my signature in presence of two witnesses.

HERMAN KERNGOOD.
